UNITED STATES PATENT OFFICE.

ADELBERT SAUER, OF PITTSBURG, PENNSYLVANIA.

ROTARY MOTOR.

SPECIFICATION forming part of Letters Patent No. 783,984, dated February 28, 1905.

Application filed July 21, 1904. Serial No. 217,578.

To all whom it may concern:

Be it known that I, ADELBERT SAUER, a citizen of the United States, and a resident of Pittsburgh, county of Allegheny, and State of Pennsylvania, have invented certain new and useful Improvements in Rotary Motors, of which the following is a full, clear, and exact specification, reference being had to the accompanying drawings, illustrating a motor embodying my invention, wherein—

Figure 1 is a vertical sectional view taken through the shaft of the motor-piston on line 1 1 indicated in Fig. 3. Fig. 2 is an end view. Fig. 3 is a cross-sectional view on the line 15 3 3 indicated in Fig. 1. Fig. 4 is a plan view of the piston.

The invention relates to a motor having a rotating piston and driven both by the impact and by the reactionary force of the motor fluid escaping from ports or passages arranged transverse to the path of rotation of the piston.

The frame of the motor comprises a base-plate 12, having the upright walls 13, that merge into the open shell 14, whose ends are 25 closed by the end plates 15, secured by bolts to flanges on the end of the shell 14. The end plates 15 carry bearing members, in which the shaft 16 of the cylindrical piston 17 is journaled. On the piston are a series of 30 radial ribs 18, extending parallel with the shaft, forming longitudinal channels 19. The latter channels are divided by a ring or flange 20, secured on the piston. From each end of each of the ribs 18 a rib 21 extends (see Fig. 35 4) first at a right angle to the rib 18 until it reaches nearly to the next rib, whereupon it extends diagonally for a distance, when it again extends in a circumferential direction until within a short distance of the next rib, 40 and so on alternately in a zigzag path until it reaches the end of the cylinder, but always extending radially from the piston. Thereby are formed an alternating series of pockets 22 and contracted passages 23.

45 A casing 24 is supported inside of the shell 14 and offset therefrom by rings 25 and 26, which casing engages the outer edges of the ribs 18 and of the ribs 21, thereby forming passages of the said channels 22 and 23. In 50 the casing 24 between the rings 25 and 26 are

a series of slots 27, that are inclined to the radius of the casing. Spaces 28 are provided in each of the end plates 15 around the ends of the casing 24, so that the outlet of the passages in the piston are in communication with the 55 spaces 29 and 30 beyond the rings 25 and 26.

The steam or other motor fluid enters the space 31 in the shell, and passing through the inclined slots 27 strikes the ribs 18 transversely, whereupon the impact will cause the 60 piston to rotate. There are preferably a less number of slots in the casing than there are ribs 18, so that some one of the ribs is always in a position to receive the greatest effect of the steam flowing through one of the slots. 65 After filling up the spaces 19 the steam passes out of the end of them through the spiral passages and thence into the spaces 29 and 30, from which it escapes through slots 32 and 33 in the lower part of the casing. The issuing 70 of the steam from these spiral passages will have a reactionary effect upon the piston similar to that in a turbine and augment the rotational effect of the steam upon the ribs 18. The steam passing into the base may 75 be there condensed by providing pipes 34, passing through the same, and caps 35 and 36, inclosing the portions of the frame supporting the tubes 34. A stream of cold water enters one of the cap-spaces through a pipe 37, 80 thence passes through the pipes 34 into the cap 36, and thence out into a pipe 38. The steam striking the cool pipes 34 will be condensed, and this water of condensation, together with the uncondensed steam, passes out 85 of the casing through an aperture 39.

What I claim as my invention is—

1. The combination of a casing, a piston set rotatably in the casing, a series of radially-disposed ribs on the piston, inlet-ports in the 90 casing for the motor fluid, means for directing the motor fluid against the ribs, a series of spirally-arranged channels in the piston extending from the spaces between the ribs to the ends of the piston, and an exhaust-port 95 in the casing connecting with the outer ends of the channels.

2. The combination of a casing, a piston set rotatably in the casing, a series of ribs radially disposed on the piston and extending 100

to the casing, radial ports tangentially disposed in the casing, a series of spirally-arranged ribs on the piston extending from the said ribs and forming spiral passages between the ribs of the piston and the inner surface of the casing and leading to the end of the piston, and an exhaust-port in the casing connecting with the ends of the spiral passages.

3. The combination of a casing, a piston set 10 rotatably in the casing, a series of ribs radially disposed in the casing, a series of spiral ribs on the piston arranged in a zigzag course and extending from the said ribs toward the end of the piston whereby spiral passages alternately increasing and diminishing in their 15 cross-sectional area are formed leading from the spaces between the latter ribs to the ends of the piston, and an exhaust-port in the casing connecting with the ends of the spiral 20 passages.

4. The combination of a casing, an outer shell concentric with the casing, longitudinal slots in the middle part of the casing disposed

at an angle to the radius of the casing, collars set between the shell and the casing one 25 at each end of the slots, an inlet into the outer shell opening into the space between the collars, a piston rotatably set in the casing, a circumferential flange set on the piston approximately midway between its ends and at right 30 angles to its axis, a series of radial zigzag ribs extending from the circumferential flange spirally around the piston and toward the ends thereof, engaging the casing with their outer edges, and forming spiral passages alternately increasing and diminishing in their 35 cross-sectional area and leading from the circumferential flange to the ends of the piston, an outlet from the outer ends of the spiral 40 passages into the space between the casing and shell, and exhaust-outlets in the shell.

ADELBERT SAUER.
